UNITED STATES PATENT OFFICE.

JOSEPH S. CLARK, OF BALTIMORE, MARYLAND.

TRUNK-CATCH.

1,177,929.

Specification of Letters Patent. Patented Apr. 4, 1916.

Application filed December 7, 1912. Serial No. 735,492.

To all whom it may concern:

Be it known that I, JOSEPH SPENCER CLARK, a citizen of the United States, residing at Baltimore, State of Maryland, 5 have invented new and useful Improvements in Trunk-Catches, of which the following is a specification.

The present invention relates to certain new and novel improvements in operating 10 means for latches for trunks or the like.

In carrying out my invention it is my purpose to provide an extremely simple but thoroughly effective catch operating member which, upon being subjected to a slight 15 pressure in one direction, will swing the catch member out of engagement with the hook of the latch, to permit of the opening of the top of the trunk with the slightest amount of physical exertion. I also propose 20 to construct a device of this character which shall embody the desirable features of simplicity, cheapness of construction, which may be easily applied, and which will perform the function for which it is adapted with accuracy and with certainty.

With the above recited objects in view, and others which will appear as the nature of the invention is more fully understood, the improvement resides in the construction, combination and operative arrangement of parts set forth in the following description and falling within the scope of the appended claims.

The accompanying drawing illustrates a 35 satisfactory reduction of my invention to practice, but the important instrumentalities thereof may be varied, and so it is to be understood that I am not to be restricted to the precise structural details shown and described, but that I am entitled to all such changes in size, shape, material, etc., as fall within the scope of my claims.

In the drawing: Figure 1 is a front elevation of a trunk latch provided with my 45 improvement. Fig. 2 is a central vertical section through the same, the latch being illustrated in applied position upon the trunk, and the dotted lines illustrating the manner in which the catch member of the 50 latch is removed from engagement with the hook member of the latch through the

medium of my improvement, and Fig. 3 is an elevation of the hook member illustrating a further means of attaching my improvement thereto.

55

Referring now to the drawing in detail, the numeral 1 designates the body of the trunk, and 2 the top therefor. The top is hingedly connected with the trunk in the usual manner, and the top is normally sustained connected with the body of the trunk through the medium of the ordinary latches.

60

The latch member comprises the spring catch-carrying member 3 which is secured to the body of the trunk, and the hook-carrying member or lift 4 which is secured to the top of the trunk, the spring catch of the member 3 co-operating with the hook of the member 4. The hook, which may be designated by the numeral 5, projects centrally from the lower edge of the member 4, and the spring catch of the member 3,

65

which may be designated by the numeral 6, is provided with a slotted projection 7, which receives the hook 5. The member 3 may also have its upper edge formed with 70 pockets 8 which are disposed to the opposite sides of the slotted extension 7, the said pockets receiving the lugs 9 which project from the lower edge of the member 4,

75

and which are disposed to the opposite sides of the hook 5. The lift member 4 may be, and preferably is, formed with the usual outwardly extending lifter 10, the opposite and lower walls of which terminate a 80

85

suitable distance above the hook 5, and the body or plate of the member 4 may be provided with a projection 11 which has its outer face centrally depressed to provide bendable fingers, such construction being 90 illustrated in Figs. 1 and 2 of the drawing. The lifter 10 is so shaped as to act as a shield to prevent accidental or inadvertent operation of the lever 12, as will hereinafter be more fully explained.

95

The numeral 12 designates the improved catch-operating device. This device is in the nature of a lever, embodying a body portion 13 which has its lower end provided with a reduced neck 14, and from which 100 projects spaced fingers 15. The neck may be provided with a substantially rectangular

lar opening 16 to provide for the reception of the member 11 of the element 4, and the fingers 15 are disposed to the opposite sides of the hook 5 when the member 12 is loosely arranged upon the lift member 4. After the member 11 is properly positioned upon the member 4, the fingers provided by the projection 11 are bent in opposite directions over the neck 14 of the lever to loosely 10 sustain the said lever upon the lift.

It will be noted by reference to the figures of the drawing that the body 13 of the lever 12 is of a size sufficient to permit of the free movement of the lever within the lifter 15 10 of the lift, and it will be readily noted that when the fingers 15 engage between the member 3 and the extension 7 of its spring catch 6, an inward pressure upon the upper portion or body of the lever 12 will swing 20 the said lever upon the member 11 to bring the catch out of engagement with the hook 5, and thus permit of the swinging or opening of the top of the trunk. It will be further apparent that the lifter 10, surrounding the lever 12 protects the said lever from accidental contact, so that the trunk may be shipped or otherwise transported without danger of the accidental operation of the said lever, and still further the 30 shield, provided by the said lifter 10, will prevent or assist in preventing any sidewise movement of the said lever 12.

By reference to Fig. 2 of the drawing it will be noted that the lever 12 is loosely connected with the member 4 beyond the center of the said lever, or, in other words, the upper portion or body of the lever terminates a greater distance away from its pivotal connection with the shield than do the fingers of the said lever, and also that the upper portion of the lever is curved or bowed outwardly from its neck, as are also the extremities of the fingers 15. This arrangement permits of the upper portion or body 45 of the lever, when the fingers 15 thereof are contacted by the spring catch 6, being tilted toward the front of the lifter 10, so that a person attempting to open the trunk will have his fingers contact with the lever to 50 swing the same upon its loose connection with the member 4 and so disengage the spring catch 6 from the hook 5 and open the top of the trunk at a single operation.

I desire that it be distinctly understood 55 that I am not to be limited to the means whereby the lever 12 is connected with the lift member 4, and in Fig. 3 of the drawing I have illustrated the neck 14 of the said lever provided with perforated ears 17 which 60 are adapted for the reception of a pintle 18 which passes through suitable openings provided in the lower side walls of the lifter 10. Such means of loosely connecting the lever with the lift being merely an illus-

tration of one of any number of various 65 methods for sustaining the lever in operative position.

From the above description, taken in connection with the accompanying drawing, the simplicity of the device, as well as the 70 method of operating the same, will it is thought, be perfectly apparent to those skilled in the art to which such inventions appertain without further detailed description. In Fig. 1, I have illustrated, by the 75 dotted lines, the ends of the shield bent over the lever, as a further means whereby the lever may be loosely arranged upon the lift plate.

Having thus described the invention, what 80 I claim is:

1. In combination with a latch embodying a hook member and a catch for engaging with the hook member, of a lever trunnioned upon the hook member, said lever including a body portion which is curved outwardly and upwardly from the hook member and a finger arranged below its trunnion and normally contacted by the catch of the latch. 85

2. The combination with a latch embodying a hook member and a catch for engaging with the hook member, of a lever mounted upon the hook member and normally engaging with the catch of the latch, the body of the lever being curved and disposed above the catch and the hook of the hook member. 90

3. In combination with a latch including a hook member and a catch for engaging with the hook of the hook member, of a lever associated with the hook member and provided with an arm disposed in contacting position with the inner face of the catch of the latch, the body of the lever being arranged above the hook member and the 100 catch. 105

4. In a trunk latch, the combination with a spring pressed catch, a second member provided with a hook which is adapted to be engaged by said catch, ears upon said member, a release member, said release member including an oval-shaped head having a depending portion arranged between said ears and a depending finger which is adapted to engage between said hook and catch and normally contacted by said catch, whereby said release member is sustained in its operative position. 110

5. In a trunk catch, the combination with a hasp, of a coöperating fastening member engaged by said hasp, a lever mounted on said fastening member and engaging said hasp, and a shield around the free end of said lever to prevent accidental operation thereof. 120

6. In a trunk fastener, the combination with a body member, of a coöperating lid member, a pivoted spring actuated hasp 125

loop carried by the body member, a retaining lug carried by said lid member to receive said hasp loop, and a lever carried by said lid member engaged by said hasp loop when in locked position and adapted to disengage said hasp loop from said lug by the outward movement of part of said lever.

In testimony whereof I affix my signature in presence of two witnesses.

JOSEPH S. CLARK.
